5 Claims. (Cl. 230—119)

1

The present invention relates to a centrifugal compressor with an approximately conical rotor for producing a high stage-pressure ratio combined with a plurality of diffusors arranged in an axial direction from that rotor. The invention consists in combining rotor blades having a radial projection in sections taken at right angles to the rotor axis in order to avoid bending stresses, but also shaped to send the medium flowing from the rotor in a direction oblique to the rotor axis, with an intermediate member provided with directing channels for first deviating that medium at approximately unchanged velocity into a direction at least approximately parallel to the rotor axis and leading to diffusors having generally straight axes in which that medium is then slowed down.

In employing the word "axes" to describe the central or median lines about which the diffusors are arranged applicant does not intend to limit such lines to the rigid geometric straightness of an axis of rotation, but rather to include lines having slight and aerodynamically unimportant departures from such straightness. See New Century Dictionary 2 vol. ed., September 1930.

The diffusors are preferably of circular cross-section. The channels of the intermediate member which guide and turn the flow from rotor to diffusors, may at the rotor end be of approximately rectangular cross-section and at the diffusor end of circular cross-section, both with about the same cross-sectional area. It is advantageous for these directing channels, and the diffusors connected to them, to be contained between an outer guide casing and an inner guide member in the form of a body of revolution symmetrical with respect to the rotor axis. The axes of the diffusors themselves may cut the rotor axis at any finite point or at infinity, or they may be arranged oblique to but not intersecting it.

In the conversion of energy in a centrifugal blower the efficiency of the diffusor plays an important part, since, as is known, only about one-half to three-quarters of the delivery pressure is produced up to the outlet of the rotor, whilst the rest exists in the issuing delivered medium in the form of kinetic energy and has to be converted as far as possible into pressure in the diffusor.

The best efficiency of all designs of diffusors is possessed by those which consist of a conically expanding pipe of circular cross-section having a straight axis. In radial compressors it is old to divide the air-stream issuing from the rotor into separate streams by means of a suitably subdivided guide spiral and to turn these streams

2

from that spiral into straight-axis diffusors lying in planes at right angles to the rotor axis. These streams are slowed down in the diffusors and thus obtain pressure, the retarded stream issuing, if required, into a bladeless spiral casing, where after further turning in planes at right angles to the rotor axis, it is led to the outlet branches. Such spirals with straight-axis diffusors have large diameters and therefore take up much space radially, so that, apart from the drawback of increasing the weight and the great cost of manufacturing such a spiral, it is difficult to fit such a compressor into a plant as an auxiliary machine. In addition, such known outlet spirals equipped with diffusors can only be adopted for centrifugal machines with radial flow of the medium handled. An obvious means of reducing the diameter of the spiral casing is to construct the diffusor with the axis bent. But then additional Coriolis and centrifugal forces make their appearance in the medium handled, causing the flow of the medium to be deflected from the guiding walls and thus giving always a worse diffusor efficiency than with straight-line diffusors. Also diffusors with cross-sections other than circular do not allow such a good efficiency to be attained in service, since the flow in the existing angles of the casing is subjected to the braking action of the walls on two sides. The alternative drawbacks of comparatively large casing diameters or diffusors with a poor degree of efficiency can both be avoided by the present invention.

Embodiments of the invention are illustrated by way of example in the accompanying drawing, in which:

Fig. 1 shows an axial cross-section of a centrifugal compressor;

Figs. 2, 3 and 4 show sections on the planes I—I, II—II and III—III of Fig. 1;

Fig. 5 shows an end view of the compressor in part section on the planes I—I and II—II of Fig. 1; and

Figs. 6—8, inclusive, represent different forms of arrangement of the diffusors.

The shaft 1 of the rotor 2 is carried in the bearings 3 and 4. The bearing 3 is arranged in the inlet casing part, and the bearing 4 in the guide member 6. At the inlet end, the shaft 1 is connected through a coupling 7 to a driving machine (not shown), for instance a turbine or an electric motor. The approximately conical rotor 2 is provided with screw-shaped blades 8, which have, as shown in Fig. 5, a radial projection in sections taken at right angles to the rotor

axis x in order to prevent bending stresses being caused by centrifugal forces. In order to obtain a high-stage-pressure ratio the rotor 2 can be driven at a correspondingly high velocity, which may in certain circumstances be greater than the velocity of sound in the medium handled, for instance at 330 metres per sec. and more, without the absolute outlet velocity of the medium delivered by the rotor 2 exceeding or reaching this velocity of sound, the tapering screw-line of the blades 8 being arranged in the direction of rotation opposite to that of the rotor and thus ensuring an outlet angle on the rotor 2 in accordance with this requirement.

The guide member 6, formed as a solid of revolution symmetrical with respect to the rotor axis x , is arranged at the outlet end of the rotor 2. Both the rotor 2 and the guide member 6 are surrounded by the casing 9, which is connected at the inlet end to the inlet casing part 5 by supporting ribs 10, and to the guide member 6 by the partition walls 11. The intermediate piece lying between the cross-sectional planes I—I and II—II is provided with directing channels 12, which are formed by the casing 9, the guide member 6 and the partition walls 11. It would be possible in the intermediate piece to form the partition walls of the channels as blade grids, which particularly for rotors with slow specific speed, whose stream issuing from the rotor requires to be greatly deviated, could be formed as split wings. The channels 12 are bent from a direction parallel to the rotor blades to a direction parallel to the diffusor axes Y in such a way that the medium flowing out from the rotor in a direction oblique to the rotor axis, is deviated into a direction at least approximately parallel to the rotor axis. At the inlet side of the intermediate piece, the channels 12 are of rectangular cross-section as shown in Fig. 2, the partition walls being then thin and offering only slight resistance to the medium flowing in. The cross-section of the channels 12 changes its shape continually along the axis of flow through the intermediate piece in order to form on reaching the transverse plane II—II, shown in Figs. 3 and 5, a circular cross-section of about the same area as the rectangular entry cross-section (I—I).

By doing without a diffusor effect in this intermediate piece, the flow is prevented as much as possible from leaving the guiding walls. Approximately from the section II—II downwards, the channels 12 lead into diffusors 13, which are for the most part straight and contained between casing 9 and guide member 6, the circular cross-sections gradually widening, so that the conversion from velocity energy into pressure energy takes place under the most favourable conditions. The axes y of the diffusors 13 may then cut the axis x of the rotor at infinity or at a finite point or may be arranged oblique to but not intersecting it, as shown in Figs. 6—8. From the diffusors 13 the medium handled arrives approximately free from twist and with components of velocity mostly parallel to the axis into the angular space 14 between the guide casing 9 and the guide member 6 and leaves it through the pipe 15 leading to the point of use.

Instead of the channels 12 and the diffusors 13 being formed as hollow spaces in a cast piece as

in the embodiment illustrated in Figs. 1—5, they could, without departing from the invention, also be made of sheet metal and so supported with respect to each other that the desired mutual position is ensured. In this way it would be possible to reduce the weight of the compressor considerably.

It would also be possible for the axes of all diffusors to be parallel to each other, but nevertheless slightly inclined to the rotor axis. Likewise the point of intersection of the diffusor axes might lie outside the rotor axis.

I claim:

1. A centrifugal compressor assembly for producing a high stage pressure ratio, including in combination an approximately conical rotor arranged to discharge at its bigger end, a plurality of stationary diffusors arranged around the rotor axis with their inlet ends toward the rotor discharge end but axially displaced therefrom, said diffusors having circular cross-sections and generally straight axes the directions of these axes deviating by less than 20° from the direction of the rotor axis, and a stationary intermediate portion between the rotor discharge end and the diffusor inlet ends provided with directing channels, matching, as to cross-section and direction, at the one end with the diffusor inlet ends and having curved axes and along these curved axes cross-sections of substantially constant area but continually variable shape, to match, as to cross-section and direction, at the other end with the discharge from said rotor.

2. A centrifugal compressor assembly as claimed in claim 1, the directing channels and the diffusors of which are contained between a guide casing and a guide member, said member forming a solid of revolution symmetrical to the rotor axis.

3. A centrifugal compressor assembly as claimed in claim 1, the axes of whose diffusors intersect the rotor axis at a finite point.

4. A centrifugal compressor assembly as claimed in claim 1, the axes of whose diffusors intersect the rotor axis at infinity.

5. A centrifugal compressor assembly as claimed in claim 1, the axes of whose diffusors being arranged oblique to the rotor axis but not intersecting it.

GEORG AUE.
